[57] CLAIM

The ornamental design for wrist watch case, substantially as shown.

DESCRIPTION

FIG. 1 is a top plan view of a wrist watch case showing my new design;

FIG. 2 is a right side elevational view thereof;

FIG. 3 is a left side elevational view thereof; and

FIG. 4 is a rear elevational view thereof.
The broken line showing of watch straps is for illustrative purposes only and forms no part of the claimed design.
